SHOWER RECEPTOR OR THE LIKE

Raymond R. Flores, Hayward, Calif., assignor to Flore-stone Products Co., Hayward, Calif., a corporation of California

Filed July 21, 1965, Ser. No. 86,236

Term of patent 14 years

(Cl. D4—4)

FIG. 1

FIG. 2

FIG. 3

FIG. 4

FIG. 1 is a top plan view of a shower receptor or the like showing my new design.

FIG. 2 is a side elevational view thereof.

FIG. 3 is a bottom plan view thereof.

FIG. 4 is a perspective view thereof.

The design is characterized by the design as shown embossed into the top surface of the receptor.

I claim:

The ornamental design for a shower receptor or the like, as shown and described.
